UNITED STATES PATENT OFFICE.

HARRY C. BUHOUP, OF CHICAGO, ILLINOIS, ASSIGNOR TO THE McCONWAY & TORLEY COMPANY, OF PITTSBURGH, PENNSYLVANIA, A CORPORATION OF PENNSYLVANIA.

COUPLING-CONTROLLING MECHANISM.

1,021,446.

Specification of Letters Patent. Patented Mar. 26, 1912.

Application filed August 29, 1910. Serial No. 579,379.

To all whom it may concern:

Be it known that I, HARRY C. BUHOUP, a citizen of the United States, residing at Chicago, in the county of Cook and State 5 of Illinois, have invented certain new and useful Improvements in Coupler-Controlling Mechanism; and I do hereby declare the following to be a full, clear, and exact 10 description of the invention, such as will enable others skilled in the art to which it appertains to make and use the same.

My invention relates to that class of railway appliances which have for their purpose the manual control of a laterally swinging 15 car coupling where it is necessary or desirable to effect the coupling of cars on a curve.

The object of the invention is the provision 20 of simple means wherein the contact or connection of the co-acting elements is such that each member of the combination may control the movement of the other and at the same time each element may move independently of the other whereby the durability and security of the controlling mechanism 25 is enhanced.

To this end my invention, generally 30 stated, embraces the combination with a coupler capable of a laterally swinging movement, of a controller element movable independently of the coupler, and an interposed contact element whereby the coupler and the controlling mechanism may not only move in unison but also independently of 35 each other.

There are other, minor, features of invention, all as will hereinafter fully appear.

In the drawings illustrating my invention, the scope whereof is pointed out in the 40 claims, Figure 1 is a plan view of the end of a car equipped with a coupler controlling mechanism embodying my invention; Fig. 2 is an end elevation of the devices illustrated in Fig. 1, the portion of the coupler which 45 extends forwardly of the carry-iron being omitted; Fig. 3 is a side elevation of the coupler, and a portion of the coupler controlling mechanism shown in Figs. 1 and 2, the car platform to which they are attached 50 being shown in vertical section; Fig. 4 is a detail sectional view of a portion of the curved supporting rail or track for the carry-iron of the coupler, and a side eleva-

tion of a portion of the carry-iron; Fig. 5 is a detail view, partly in section of one end 55 of the supporting rail for the carry-iron, showing the relation thereto of the controller and the carry-iron; Fig. 6 is a plan view of the end of a car equipped with a modified form of the coupler controlling mechanism 60 illustrated in the preceding figures of the drawings; Fig. 7 is a detail view in elevation and partly in section of one end of a supporting rail for the controller member, 65 a guide pulley for the flexible controller member, and a sheave and coiled spring for actuating the controller member shown in Fig. 6. Fig. 8 is a detail plan view of one end of the supporting rail, the controller member, the guide pulley and the spring 70 actuated sheave, shown in Fig. 6, the supporting rail being in section. Fig. 9 is a view in elevation of a portion of the supporting rail, controller member, carry iron, 75 and slide or floating contact, shown in Fig. 6. Fig. 10 is a detail view, partly in plan and partly in horizontal section, showing the supporting rail, carry iron and the slide block or floating contact illustrated in Fig. 6; and Fig. 11 is a detail view, partly in 80 side elevation and partly in vertical section, showing the supporting rail and carry iron illustrated in Fig. 6.

Like symbols refer to like parts wherever 85 they occur.

I will now proceed to describe my invention more fully, so that others skilled in the art to which it appertains may apply the same.

In the drawings, A is the coupler and B 90 the draft gear which is yieldingly and pivotally attached to the car in the usual or any approved manner.

The coupler itself forms no part of the present invention, and therefore may be of 95 any desired form, provided it satisfies the above-noted requirements.

Preferably the coupler will have a limited vertical as well as a lateral movement, and for this reason the opening in the carry-iron, 100 or its equivalent, is of sufficiently greater height than the coupler to permit of the desired vertical movement of the coupler.

In the present instance the means illustrated for supporting and permitting the 105 laterally swinging motion of the coupler

consist of a curved track or supporting rail 1 attached to the under side of the car platform, and a carry-iron 2 adapted to travel on the supporting rail 1. The supporting rail or track 1 may be, and preferably is, formed with a ledge or shoulder 1^a for the support and guidance of the controller element, where, as is preferably the case, said element is a chain, or of a flexible character, 5 and the supporting rail is provided at its opposite ends with stops 1^b to limit the lateral travel in either direction of the carry-iron 2 and the coupler A.

The carry-iron 2 as shown in the drawings is one having a T-slot 2^a for the reception of the bottom flange of the supporting rail or track 1 on which it travels, and an opening 2^b for the passage of coupler A, said opening 2^b being of sufficiently greater height 10 than the coupler to permit of a limited vertical play of the coupler in the carry-iron. The opening 2^b may be closed by the bottom member 2^c which is bolted or otherwise secured to the upper member of the carry-iron 15 so as to support and confine the coupler within the carry-iron 2.

Upon the upper surface of the carry-iron 2 is a contact member 2^d which projects into the path of a similar contact member attached to or carried by the controller member 5.

Secured to and extending downwardly from the under side of the car platform, at or adjacent to the ends of the curved supporting rail or track 1, are brackets 3, on each of which is journaled a vertical shaft 3^a having secured thereto at its upper end a sprocket wheel 3^b and at its lower end a bevel gear 3^c. Horizontally journaled in 35 each of said brackets 3 is a second shaft 4 provided with a bevel gear 4^a which meshes with the bevel gear 3^c, and a hand wheel 4^b for manually rotating said shafts 4, 3^a to operate the controller member 5.

45 The controller element which has a movement independent of the coupler and which is preferably of a flexible nature, is shown in Fig. 1 of the drawing as an endless chain 5 that passes around the curved supporting rail or track 1, and the sprocket wheels 3^b and is supported on the ledge or shoulder 1^a of the supporting rail 1. Secured to or carried by the controller element 5, are contact elements 5^a which co-act with the contact element 2^d of the carry-iron 2. The contact elements 5^a carried by the controller element 5, are so relatively disposed thereon that when in given positions with relation to the longitudinal axis of the car and 50 the normal or central position of the coupler, the coupler may move laterally in either direction independently of the controller element 5.

60 The construction illustrated in Figs. 1 to 4, inclusive, of the drawings is the simpler

form of the mechanism, and, therefore for many reasons the preferable one. There are, however, many modifications thereof which will readily suggest themselves to the skilled mechanic, as for instance the construction 70 shown in Figs. 6 to 11, inclusive, of the drawings. In this last named construction it will be noted that the bottom flange 1^c of the curved supporting rail or track 1 is the equivalent of the ledge 1^a of the construction 75 shown in Figs. 3 and 4, and serves as the support of the controller element 5, and that stops or projections 1^d at the ends of supporting rail 1 are the equivalents of stops 1^b in Figs. 1 and 2 of the drawings, and limit the travel in either direction of slide block 8, carry-iron 2 and coupler A. The controller element 5 instead of being an endless chain as illustrated in Fig. 1, is one 80 whose opposite ends pass around loose or guide pulleys 6 and are secured to sheaves 7 having shafts 7^a journaled in brackets attached to the under side of the car platform. The shafts 7^a are provided with hand-wheels 7^b whereby the shafts may be rotated to effect the desired travel of the controller element 5 in either direction. In some instances it may be found desirable to combine 85 with the sheaves 7 and shaft 7^a a coiled spring 7^c located within the sheave 7 which spring will be wound up as the controller is operated by the shaft and sheave, and will react to return the sheave and the controller to their original and normal positions as 90 soon as the sheave is released.

In the modification shown in Figs. 6 to 11 of the drawings, instead of providing a contact member 2^d on the top of the carry-iron 2 for engaging the contact member 5^a of the controller member, there is shown a slide block 8. This slide-block is movable on the controller element 5 and is engaged and moved by the contact member 5^a thereof, and in turn contacts or engages the side of the carry-iron 2 and imparts motion to the carry-iron and coupler. There are two of these slide-blocks or floating contacts 8 employed, one on each side of the carry-iron, and they are each, preferably, provided with projecting tongues 8^a which serve to maintain the proper relation of the controller member and the carry-iron. When in contact with the carry-iron, the tongues 8^a which travel under the controller member enter the T-slot 2^a of the carry-iron.

100 Assuming the coupler A to be in its normal or central position as shown in Fig. 1 of the drawings, and it is desired to move the coupler into one of its lateral positions so as to couple on a curve; one of the hand-wheels will be rotated to cause the controller member 5 to travel in the direction in which it is desired to move the coupler. In the course of the travel of the controller member one of the contact members 5^a will en- 105

gage the contact member 2^d (Fig. 2) on the carry-iron 2 and move the carry-iron and coupler into the required position to make the coupling. When the coupling has been 5 made, should the coupler swing farther in the same direction, no movement of the controller will ensue, nor will it occur until such time as the coupler swings in reverse direction past the position wherein the coupling was made. When this takes place the contact member 2^d on the carry-iron will engage the contact members 5^a of the controller 10 5 and reverse the travel of the controller until such time as the coupler has 15 reached the limit of its movement in the reverse direction, after which the movement of the controller member will cease, and will not again occur until the controller is manually operated.

20 In case of the construction shown in Figs. 6 to 11 of the drawings, the operation of the controller mechanism is substantially the same as in the construction shown in Figs. 1 to 5, except that the contact member 5^a 25 instead of directly engaging the carry-iron engages it through the intermediacy of slide-block or floating contact 8 which is picked up by the contact member 5^a of the controller and moved into contact with the 30 carry-iron. In this form of devices, the slide-block or floating contact 8 will be arrested by the stops 1^d when the extreme lateral movement of the coupler, in either direction, has occurred, and the blocks 8 will 35 remain in position at the opposite ends of track 1 (see Fig. 6) until the controller member 5 is again manually operated to move the coupler, but the contact member 5^a may continue to move with the controller 40 member 5 back and away from the slide-block.

It is to be noted that in the modification, Fig. 6 of the drawing, the coupler is shown as in the central position, and the floating 45 contacts or slide blocks 8 at the extreme limit of their movement, viz., at opposite ends of the supporting rail 1 and resting against the limit stops 1^d. If now it is desired to move the coupler to either side of 50 its central position, as for coupling on a curve, the proper sheave is rotated to obtain the desired direction of travel of the controller 5, whereupon the contact member 5^a which is back of the slide-block or 55 floating contact 8 that is to be moved will carry said slide block forward into contact with the coupler and cause the slide block 8 to push the coupler into the desired position for coupling. As soon as the sheave 60 and controller are released, the coiled spring which has been energized by the turning of the sheave to cause the travel of the controller will react to reverse the movement of controller member 5 and carry the contact 65 5^a to its first position, but will leave the

slide-block 8 in position adjacent to the coupler, which position the floating contact 8 will continue to occupy until the movement of the coupler also returns it to its first position. In this travel of the controller 5 one contact member 5^a thereon, will of course have to pass around one of the guide pulleys 6 and on to the sheave on which the controller chain 5 is being wound, but as this contact member 5^a does not exceed an inch in length and so projects but slightly the slack of the controller 5 will readily permit it to pass the guide pulley 6, and any unevenness of the windings of the controller chain 5 on the sheave becomes a matter of no material importance, as it will not affect the operativeness of the devices.

Having thus described my invention, what I claim and desire to secure by Letters Patent is:

1. In a mechanism of the character indicated, the combination of a pivotally mounted coupler, and a flexible controller member whereby said coupler may be caused to turn on its pivot, said coupler and said controller member being independently movable.

2. In a mechanism of the character indicated, the combination of a pivotally mounted coupler, a flexible controller member which is movable to cause said coupler to turn upon its pivot and which is also movable independently of the coupler, and means movable with the controller member to cause said coupler to turn on its pivot.

3. In a mechanism of the character indicated, the combination of a pivotally mounted coupler, a movable controller member, said controller member being movable independently of the coupler, and means movable by and also independently of the controller member and of the coupler to cause the coupler to turn on its pivot.

4. In a mechanism of the character indicated, the combination of a pivotally mounted coupler, an endless flexible controller member movable independently of the coupler, and means movable with the controller member and also independently of the coupler to cause the coupler member to turn on its pivot.

5. In a mechanism of the character indicated, the combination of a pivotally mounted coupler, a flexible controller member movable independently of the coupler, and means movably connected to the controller member and adapted to turn the coupler on its pivot, said means being movable by the coupler when the latter swings in one direction and being unaffected by a swinging movement of the coupler in the opposite direction.

6. In a mechanism of the character indicated, the combination with a pivotally mounted coupler, of a supporting rail, a

carry-iron supporting said coupler and
slidably mounted on said supporting rail,
and a flexible member guided by said sup-
porting rail and having means for actuating
5 said carry-iron.

7. In a mechanism of the character indi-
cated, the combination with a pivotally
mounted coupler, of a curved rail, a flexible
member guided by said rail, and means

actuated by said flexible member to cause 10
said coupler to turn upon its pivot.

In testimony whereof I affix my signa-
ture, in presence of two subscribing wit-
nesses.

HARRY C. BUHOUP.
